UNITED STATES PATENT OFFICE.

FRED N. STEVENS, OF SALEM, VIRGINIA.

ROOFING TONGS.

Application filed August 9, 1927. Serial No. 211,797.

This invention relates to improvements in metal bending and seam-forming or crimping tongs generally identified in the art as roofing tongs and therefore herein-
5 after referred to as such, the invention having for one of its principal desiderata a means to provide roofing tongs having gage means thereon whereby the usual standing seams and flat locking seams of sheet-metal roofing
10 and similar material may be formed of any desired width simply by selective adjustment and operation of certain of the gage means, hence dispensing with the need of a multiplicity of tongs for forming different sized seams.

It is also an object of the invention to provide tongs of the character mentioned having a plurality of differently positioned gage pins or stops, mounted in certain of the jaws thereof, normally arranged in in-
20 operative positions so as not to interfere with the metal crimping or bending operation of one side or width, but capable of selection and movement to an operative position at substantially right angles to the jaws and cooperable with the opposite jaw whereby to accurately and uniformly gage the forming of another bending or crimping of a different width.

30 The invention also aims to provide roofing tongs having independently and selectively operable gages which when brought into operative positions will be positively and rigidly retained in such positions during a metal bending or crimping operation, thus insuring work of a uniform size and width throughout their period of usage.

Other objects of the invention will be in part obvious and in part pointed out hereinafter.

40 In order that the invention and its mode of operation may be readily understood by those skilled in the art to which it appertains, I have in the accompanying illustrative drawings and in the detailed following description based thereupon, set out one possible embodiment of the invention.

In these drawings:

Fig. 1 is a side elevation of the improved
50 tool;

Fig. 2 is an end elevation of the same;
Fig. 3 is a fragmental side elevation of one of the jaws showing the provision of springs for normally retaining the adjustable gage fingers in operative or inoperative 55 positions;

Fig. 4 is a similar and enlarged view illustrating the mounting of the adjustable gage fingers; and

Fig. 5 is a transverse section taken on 60 the line 5—5 of Fig. 4.

Having more particular reference to the drawings in connection with which like characters of reference will designate corresponding parts throughout, the improved tongs 65 may be stated to comprise the usual relatively opposed flat and elongated jaws 1 and 2 between which the portions of sheet metal to be bent or crimped thereby are engaged during a bending or crimping operation; the intermediate portions of these jaws being pivotally interconnected through the medium of relatively crossed levers 3 and 4 having flattened bearing portions through which a pivot bolt or pin 5 is passed and secured against displacement through the medium of a nut 6 or similar element, frictional contact between the adjacent bearing portions of said levers 3 and 4 being maintained by a spring washer 7 so that the jaws 80 will be caused to remain in their opened positions when moved thereto under influence of the levers 3 and 4, thereby facilitating the selective operation of the gage pins (hereinafter more fully described) and the 85 engagement of the metal to be bent or crimped between said jaws and against said pins.

Handles 8 are detachably engaged with the free extremities of the crossed and pivotally interconnected levers 3 and 4 for an obvious purpose; and by reason of their detachable connection to such levers, they obviously may be removed when the tool is not in use, for convenience in handling and economy of space in the kit of a user.

Formed in the opposite end portions or at other practical points in the jaw 1 are transversely disposed pairs of longitudinal- 95 ly extending ways or pockets 9, said pockets 100

or ways being of complementary size and shape and having their outer sides closed through the medium of longitudinally split or slit spring bearing and locking fingers 10, such fingers being secured against displacement with respect to the jaw 1 and said ways or pockets 9 by screws 11 or other appropriate fastening devices engaged in adjacent portions of said jaw.

10 Gage pins or stops generally indicated by the numeral 12 are adapted to be received in each of the ways or pockets 9, being of lengths approximately corresponding to said ways and having shouldered attaching portions or heads 13 formed on certain of the ends thereof; cross-sectionally squared bearing openings being formed transversely of each of said portions or heads 13, as indicated by the numeral 14, whereby to receive, 15 at times, the cross-sectionally squared portion 15 of a pin shaft 16 therethrough, while at other times, the cross-sectionally circular portions of said pin shafts are adapted to be engaged in said openings.

20 The pin shafts 16, of which there are two, are rotatably and transversely slidably mounted in bearing openings provided therefor in portions of the jaw 1 adjacent to and aligning with the openings 14 formed 25 in the heads of the gage pins 12, being retained against transverse displacement with respect to the adjacent portions of said jaw 1 by bushings 17 engaged in and having driving fit with portions of the aforesaid 30 openings in said jaw receiving the pin shafts; the outer ends of each of the pin shafts carrying finger-engaging pieces 18 thereon for obvious purposes.

35 That the opposite or remaining jaw 2 may be swung or moved to its closed position or in position contacting with the adjacent side of the jaw 1, pairs of transversely disposed slots 19 and 20 are formed in said jaw 2 at points whereat they will receive the free 40 ends of the gage pins 12 therethrough when the latter are in their operative positions at substantially right angles to the jaws; it being noted in this connection that the slots 19 may be of slightly greater lengths 45 than the slots 20, whereby to compensate for the difference in the arc of travel of those particular gage pins engaged therethrough with closing or similar pivoting of the jaws 1 and 2.

50 Fixed or stationary gage pins 21 are mounted upon the inner side of the jaw 1 in proximity to the opposite end portions thereof and preferably outwardly with respect to the movably mounted gage pins 12; 55 the outer or free portions of these latter gage pins 21 being curved upon themselves as indicated by the numeral 21' so that with pivoting of the jaws 1 and 2, said free portions of said gage pins 21 will freely pass 60 through ways or slots 22 provided therefor

in corresponding end portions of the opposite jaw 2, it being noted in this connection that said slots 22 are disposed transversely of the jaw 2 and in substantially parallelism to the first-mentioned slots 19 and 20.

65 In using my improved roofing tongs, the gage pins 12 are normally retained in their inoperative positions within their respective ways or pockets 9, being releasably held in these positions by the engagement of the adjacent spring fingers 10 with the flattened side portions of the shouldered heads 13. With the gage pins 12 in their inoperative positions just described, it will be understood that the tongs may be used by a worker for the bending or crimping of a seam or the like of a maximum predetermined width merely by engaging the proper portions of the sheet metal or other material to be so worked therebetween and forcing the handles 8 of the crossed and pivotally interconnected levers 3 and 4 so as to bring the jaws 1 and 2 together in a clamping-like fashion; the free portions of the fixed gage pins 21 passing through the slots 22 in the 70 jaw 2 during such an operation.

75 When it is desired to form a seam, bend, or crimp of a slightly lesser width than that formed with usage of the fixed gage pins 21, the finger pieces 18 of the several pin shafts 16 are grasped by the user and pulled outwardly, thereby transversely sliding said pin shafts 16 through their respective bearing openings in the jaw 1 and bringing the cross-sectionally squared key portions 15 thereof 80 into engagement with the cross-sectionally squared openings 14 in the shouldered heads of the outermost gage pins 12. At this time, the pin shafts 16 are rotated and thereby the selectively engaged gage pins 12 will 85 be caused to swing outwardly from their respective ways or pockets 9 to positions at substantially right angles to the jaw 1, affording when in such positions, effectual 90 gage means for bringing about a bending or crimping of a seam or other device of a predetermined and uniform width; this bending or crimping being accomplished by a repeating of the pivoting movement of the jaws 1 and 2 during which the free extremities of the operatively positioned gage pins 12 will pass through the slots or ways 19, 95 hence permitting the adjacent sides of said jaws 1 and 2 to be brought into proximity 100 to each other.

105 Should it now be desired to form a seam or other device of even less width than that capable of being produced with usage of the gage pins 21 and the previously operated gage pins 12, said last-mentioned gage pins 125 are swung to their inoperative positions within their respective pockets 9 by a reverse rotation of their particular pin shafts 16, subsequently to which said pin shafts 130 are slid inwardly and transversely of the

jaw 1 so as to disengage the squared key portions 15 from the previously engaged openings 14 of the aforesaid gage pins 12 and to bring such key portions into snug engagement with the squared openings of the innermost gage pins 12. At this time, the pin shafts 16 are rotated whereupon said innermost gage pins 12 will be swung to positions at substantially right angles to the 10 jaw 1 and thus will form effectual gage or stop means for effecting a seam or bend or crimp of a width less than that capable of being produced through the usage of the aforesaid gage pins 21 and 12; the 15 pivoting of the jaws 1 and 2 being again repeated, during which the extended and free portions of the now operatively positioned and innermost gage pins 12 will pass through the slots 20 of the jaw 2.

20 In this connection, it will be noted that the spring fingers 10 adjacent the various ways or pockets 9 of the gage pins 12 will serve as means for releasably retaining each of said gage pins in their inoperative positions within said pockets, and furthermore, that when said pairs of gage pins 12 are moved to their operative positions they will likewise be releasably retained in these latter positions by spring-bearing-like engagement of the fingers 10 upon the flattened portions of the extremities of the shouldered portions or heads 13, hence insuring the positioning of the free extremities of the operated gage pins 12 so that they will freely 30 engage in and pass through their respective slots 19 and 20 in the jaw 2.

Obviously the rotatable and transversely slideable pin shafts 16 afford means whereby said gage pins 12 may be independently and 40 selectively operated, and at the same time will not interfere in any manner whatsoever with the normal mode of usage of the tongs.

Manifestly the construction shown is capable of considerable modification, and such modification as is within the spirit of my claims I consider within the scope of my invention.

I claim:

50 1. In combination with tongs of the character described, pairs of correspondingly positioned gage pins mounted on one of the jaws thereof, means for operating each pair of pins whereby said pins may be selectively moved to positions at substantially right angles to the jaws, the remaining jaw having ways therein for receiving the free portions of the pins, when in operative positions, therethrough.

60 2. In combination with tongs of the character described, gage pins mounted on one of the jaws thereof, means to permit of selective engagement with each pin whereby said pins may be independently operated to 65 positions at substantially right angles to the

jaws, the remaining jaw having ways therein for receiving the free portions of said pins therethrough when in operative positions.

3. In combination with tongs of the character described including movably interconnected jaws, one of said jaws having pairs of transversely disposed and longitudinally extending ways formed therein, gage pins normally received within and longitudinally of said ways, certain of the extremities of said gage pins having cross-sectionally squared openings formed therein, pin shafts engaged in bearing openings in said first-mentioned jaw each having a cross-sectionally squared key portion thereon, said pin shafts being rotatable and transversely slideable with respect to the jaw receiving the same and adapted to have the cross-sectionally squared key portions thereof engaged in either of the squared openings in the extremities of said gage pins whereby with rotation of said shafts to swing said gage pins to operative positions at substantially right angles to said jaw, and the remaining jaw having transverse ways therein for receiving the free portions of said pins when in operative positions, therethrough.

4. In combination with tongs of the character described including movably interconnected jaws, one of said jaws having pairs of transversely aligned and longitudinally extending pockets formed therein, gage pins normally received within said pockets having cross-sectionally squared openings formed in certain of the extremities thereof, shaft pins passed through bearing openings in portions of said first-mentioned jaw and each thereof having cross-sectionally squared key portions adapted to be selectively engaged in the cross-sectionally squared openings in the extremities of said gage pins, said pin shafts being rotatable and transversely slideable with respect to the jaw receiving the same whereby to permit of selective engagement of either of said pins of the pairs and the swinging of the same to operative positions at substantially right angles to said jaw, fixedly mounted gage pins on said first-mentioned jaw beyond said first-mentioned gage pins, and the remaining jaw having transverse slots formed therein for receiving the free portions of said gage pins therethrough at times.

5. Roofing tongs comprising in combination a pair of jaws, a plurality of gage members mounted upon one of said jaws, a shaft journaled within one of said jaws, and means connecting said gage members to said shaft whereby they may be selectively moved into and out of operative position.

6. Roofing tongs comprising in combination a jaw, gage members pivotally mounted within said jaw, means for normally retaining said gage members in inoperative position within said jaw, and means for causing

said gage members to be selectively projected from said jaw, substantially as and for the purpose specified.

7. A roofing tong comprising in combination a pair of pivotally connected jaws, a plurality of gage pins pivotally mounted within one of said jaws, the other of said jaws having a plurality of openings therein through which may project at times said

gage pins, means for operating said pins whereby they will project through the opening of said second-mentioned jaw, and means whereby said pin-operating means may be selectively connected thereto.

In witness whereof I have hereunto set my hand.

FRED N. STEVENS.
